Primary Examiner — Sharon S Oum(74) Attorney, Agent, or Firm — McGarry Bair PC(57) CLAIM

The ornamental design for a ceiling fan light kit as shown and described.

DESCRIPTION

FIG. 1 is a bottom perspective view of a ceiling fan light kit in the environment of a ceiling fan, showing my new design; FIG. 2 is a bottom perspective view thereof, having the ceiling fan environment removed;

FIG. 3 is a top view thereof;

FIG. 4 is a bottom view thereof;

FIG. 5 is a front view thereof; and,

FIG. 6 is a side view thereof.

Portions of the ceiling fan light kit and the ceiling fan environment shown in broken line form no part of the claimed design.
